Attorneys.

UNITED STATES PATENT OFFICE.

PAUL O. STRIBLING, JR., OF ATLANTA, GEORGIA.

INTERNAL-COMBUSTION ENGINE.

Application filed January 13, 1927. Serial No. 160,935.

This invention relates to an internal combustion engine and particularly to that type of engine in which a cylindrical piston and two fixed heads cooperate to form longitudinally aligned combustion chambers at each side of the piston.

An object of the invention is to provide a simple and efficient construction of the type stated in which the ports are controlled by sleeve valves. Further objects of the invention are to provide an engine of the type stated which may be readily assembled and in which the escape of gases around the moving parts is substantially eliminated.

These and other objects of the invention will be apparent from the embodiment of my invention which is described in the following specification and is illustrated in the accompanying drawings, in which drawings

Fig. 1 is a central cross-section through a cylinder and piston constructed in accordance with the invention, the valve mechanism being diagrammatically represented;

Fig. 2 is a fragmentary, longitudinal and central section through a single cylinder of the engine;

Figs. 3 and 4 are side and end elevations respectively of the piston; and

Fig. 5 is a side elevation of a sleeve valve.

In the drawings, the numeral 1 indicates the body or casing of the engine, which may be of any suitable double-walled construction providing a water jacket 2. The upper end 3 of the casing provides a fixed cylinder head which is preferably water-cooled and is provided with an axial opening for receiving the spark plug 4. The head 3 has a peripheral wall which is spaced from the cylinder wall formed by the body 1 and which carries the junk ring 5 and packing rings 6. Sliding sleeve valves 7, 8 respectively control the admission and exhaust of gases through the inlet and outlet ports 9, 10 respectively. As shown in Fig. 5, the port openings in the valve sleeves, and particularly in the inner sleeve 8, take the form of a number of comparatively narrow openings between the longitudinal ribs or bars 8. The ribs 8' prevent the packing rings 50 from projecting into the valve ports of the sleeve.

The upper portion of the piston 11 which

cooperates with the upper head 3 to form one combustion chamber is provided with the usual packing rings 6. The piston 11 is much longer than is customary in engines of the single combustion chamber type and at its lower end is provided with two diametrically opposed extensions 12 to which the bearing bracket 13 carrying the wrist pin 14 is fixed. The connecting rod 15, crank shaft 16 and valve operating mechanism 17 may be of any desired construction.

The elements so far as described above comprise the usual Knight engine having a single combustion chamber. In accordance with the invention a second combustion chamber is provided between the piston head and a lower fixed head 18 which lies within the lower portion of the cylindrical wall or skirt 19 of the piston and is supported by the crank case structure 20 in any appropriate manner. The lower head 18 is provided with a water cooling chamber 21 and 70 passages 22 extend from the cooling jacket to connect the same to the water circulating system. The lower head 18 is provided with a socket 23 having a fixed contact 24 at the base thereof which is connected to the ignition system by a lead 25. The spark plug 26 is provided with a terminal 27 which engages the contact 24 when the spark plug is screwed into the socket. The spark plug 26 is introduced through the spark plug opening in the upper head and a central opening in the head of the piston 11, which piston opening is then closed by a plug 28. The spark plug 26 may be inserted with a long socket wrench after removing the upper 90 spark plug 4 and the piston plug 28. The lower head is provided with the usual junk ring 29 and packing rings 6.

The lower portion of the engine casing is provided with inlet and outlet ports 30, 31, respectively, and the lower portions of the sliding sleeves 7 and 8 are provided with ports for controlling the flow of gases through the inlet and exhaust ports. The walls of the piston skirt 19 are provided with a plurality of openings 32 for co-operation with the inlet ports of the valves 7, 8 and with a similar series of exhaust openings. As shown in the drawings, the inlet and

exhaust passages through the piston wall take the form of substantially rectangular openings provided between circumferential bands 34 and longitudinal bars 35. The 5 shape of the openings may be varied within wide limits so long as there are provided longitudinal bearing surfaces such as the inner walls of bars 35, to prevent the rings of the lower head 18 from entering the openings and there are circumferential bands 10 providing seats for packing rings 36. The several longitudinal bearing surfaces need not be in axial alinement, and the circumferential bands need not be substantially 15 transverse to the piston axis, but I believe such arrangements to be preferable and therefore have illustrated inlet and exhaust passages, each of which comprises a plurality of polygonal slots, the slots of each 20 group being arranged in transverse and longitudinal alinement.

The manner in which the engine operates will be understood by those familiar with this art, since the invention does not reside 25 in a new method of operation but in the specific structural details which cooperate to reduce the engine weight per horse power to a minimum. The engine illustrated in the drawings operates on a four-stroke cycle 30 but suitable changes in the valve timing mechanism and in the location of the valve ports will permit operation on a two-stroke cycle.

The arrangement of the ports in the piston 35 skirt 19 and of the rings between adjacent pairs of transversely alined ports is an important feature. The explosion pressure within the lower combustion chamber is transmitted through the ports in the piston 40 to the inner sleeve of the valve mechanism. The packing rings however prevent the escape of gases along the outer surface of the piston and thereby prevent the explosion pressure from reaching the ports of the inner 45 sleeve.

The two combustion chambers are so designed that they develop substantially equal power. The location of the spark plug 26 at the center of the lower head 18 and in 50 longitudinal alinement with the upper spark plug 4 assists in securing uniformity in the operation of the two combustion chambers.

It is to be understood that the invention 55 is not limited to the particular embodiment which is shown in the drawings, since various changes may be made in the several parts, their relative size, shape and arrangement, without departing from the spirit of my invention as set forth in the following 60 claims.

I claim:

1. An internal combustion engine of the 65 type comprising a cylinder having a head, a hollow piston movable in said cylinder forming a combustion chamber with one end

thereof, a second head positioned within the skirt of said piston and cooperating therewith to form a second combustion chamber, said sleeve valves between the wall of said cylinder and the skirt of said piston, characterized by the fact that the skirt of said piston is provided with sets of longitudinally spaced inlets and exhaust openings providing 70 passages for the flow of gases into and out of said combustion chamber, and packing 75 rings are arranged on said piston between adjacent longitudinally spaced openings.

2. The invention as set forth in claim 1, wherein each of said sets of openings in 80 the skirt of said piston is defined by circumferential bands and longitudinal bars, and packing rings located in seats formed in 85 said circumferential bands.

3. In an internal combustion engine, a 90 cylinder having a head, a hollow piston movable in said cylinder and forming a combustion chamber with one end thereof, a second head positioned within the skirt of the piston and cooperating therewith to form a second 95 combustion chamber, sleeve valves between said cylinder and said piston, packing rings on said heads and piston, and gas passages through said sleeves and piston skirt, each 100 of said passages comprising a plurality of 95 openings of such dimensions that said packing rings cannot enter the same.

4. An internal combustion engine of the 105 type including a hollow piston movable within a cylinder and between the cylinder head 100 and a second head which is located within the skirt of the piston, characterized by the fact that the inner head is provided with a threaded recess for receiving a spark plug, the cylinder head and piston head having 110 threaded apertures therethrough permitting the introduction of a spark plug, the piston head aperture being closed by a removable cap and the cylinder head aperture being 115 adapted to receive a second spark.

5. A hollow piston for use in an engine 120 of the type having a cylinder head and a second head mounted on the crank case, said piston having inlet and exhaust passages through the skirt thereof, characterized by 125 the fact that said passages each comprises a plurality of openings which are longitudinally spaced from each other, and packing is provided on the skirt of said piston between adjacent longitudinally-spaced openings.

6. A hollow piston for use in an engine of 130 the type having a cylinder head and a second head mounted on the crank case, said piston having inlet and exhaust passages through the skirt thereof, characterized by the fact that said passages each comprises a plurality of openings arranged in transverse and longitudinal alinement, and a packing ring is provided on the piston skirt be- 135

tween adjacent sets of transversely-alined openings.

7. The invention as set forth in claim 5, wherein said piston terminates in two diametrically disposed extensions, and bearing blocks are mounted on said extensions and adapted to receive a wrist pin.

8. The invention as set forth in claim 5, wherein the end of said piston is provided with an aperture permitting the passage ¹⁰ therethrough of a spark plug, and a closure therefor.

In testimony whereof, I affix my signature.

PAUL O. STRIBLING, JR.
